UNITED STATES PATENT OFFICE.

JOHANN STUMPF, OF BERLIN, GERMANY.

STEAM-ENGINE.

994,484.

Specification of Letters Patent. Patented June 6, 1911.

Application filed November 16, 1910. Serial No. 592,704.

To all whom it may concern:

Be it known that I, JOHANN STUMPF, a subject of the Emperor of Germany, residing at 33 Kurfürstendamm, Berlin W., 5 Germany, have invented certain new and useful Improvements in Unidirectional-Flow Steam-Engines, of which the following is a specification.

This invention relates to uni-directional flow steam engines, that is engines in which the working steam enters the cylinder at one end and exhausts through ports in the cylinder covered and uncovered by the piston at and near the end of its working 10 stroke. In such engines the steam once it has entered the cylinder never returns on its path before exhausting therefrom, hence the name uni-directional flow. In such engines the points at which release and compression begin are never varied so that when starting or when running at high loads, an engine properly designed for its ordinary normal load, will give excessive compression. To avoid this I propose to employ an 15 auxiliary exhaust valve and the present invention relates to a novel construction of auxiliary exhaust valve which is automatic in operation and may be effectively and simply cut out at times when not required. 20 By cutting out my auxiliary exhaust valve in this way, when not required, the said valve does not interfere with the economic working of the engine during normal running.

30 The invention is illustrated in two convenient modifications in the accompanying drawings and the novel features of this invention will be pointed out in the claims.

35 In the drawings:—Figure 1 is a vertical section through the cylinder of an engine having an auxiliary exhaust valve according to one form of this invention. Fig. 2 is a section similar to Fig. 1 and showing another form of the invention. Fig. 3 is a 40 detailed view of the automatic valve employed in Fig. 2.

45 In carrying the invention into effect according to the form illustrated the engine cylinder *a* in which the piston *k* moves, has, leading from the region of the inlet end, an exhaust passage *c* which is controlled by a cock *c'*. The exhaust passage *c* opens into a casing *b* in which a steam operated valve *f* is adapted to move. Leading from the inlet 50 end of the cylinder there is a pipe *d* having a valve *d'* and this pipe opens into the end.

of the casing *b*. The steam controlled valve *f* comprises two pistons connected by a central narrow neck and the distance apart of the piston parts *f f* is such that when one 60 of the ports *c* is open, the other is closed. The operation of this device is as follows:— During starting the cocks *c' d'* are opened. When the steam is passed through one of the main steam valves, *m'* for instance, the 65 high pressure steam passes into the cylinder and also through the pipe *d* to the casing *b*. The valve *f* is in consequence pressed to the left, so that the left-hand exhaust port *c* is uncovered and the steam from the left-hand 70 end of the cylinder *a* may not only exhaust through the ports *p* in the cylinder which are controlled by the piston but also through the auxiliary exhaust passage *c* to the casing *b* and thence to the auxiliary exhaust outlet 75 *h*. This state of affairs continues until the compression pressure on the left-hand side of the piston *k* is greater than the steam pressure on the right-hand side of the piston *k*. Since the compression pressure is not 80 allowed to rise very quickly owing to the exhaust passage *c* being open, this auxiliary exhaust will continue for a very considerable part of the stroke from right to left and thereby only a very low compression will 85 be attained, such as is sufficient to meet the requirements during starting or at low loads.

In the form illustrated where the exhaust passage *c'* does not open into the extreme end of the cylinder but only in the region 90 of the inlet end the piston *k* in its stroke as can be seen at the right-hand side of the figure, covers the auxiliary exhaust passage which is thereby automatically cut out so that sufficient compression is secured to insure proper cushioning and also to insure that the valve *f* is operated by inlet steam before the passage *c* is uncovered at the inlet end by the piston. In this way it is impossible that live steam can escape through the 100 auxiliary exhaust passage *c*. The point at which the auxiliary exhaust pipe *c'* opens into the cylinder may be determined by the conditions under which the engine is intended to work.

According to the form of this invention illustrated in Figs. 2 and 3 I omit the pipes *c* in Fig. 1 and modify the construction of the valve. According to this form the main exhaust takes place from ports *q* which are 110 controlled by the piston *q'* at and near the end of its working stroke. The auxiliary

exhaust takes place through pipes r which may be cut out by cocks s . The pipes r open into a casing r' in which is arranged a valve t of the form shown in Fig. 2. The valve t has two closing members t' connected by the spindle t^2 which is suitably guided in a boss t^3 on the casing. From the center of the casing r' there leads the exhaust pipe v . The operation of this device is as follows:—

- 10 When the engine is running with normal loads the cocks s are closed so that the engine works as an ordinary uni-directional flow steam engine. When starting or during overloads and it is desired to reduce the 15 compression the cocks s are opened by means of their actuating rod s' . When working steam enters the cylinder it passes by the pipe r to one side of the double valve t and presses that side against its seat thereby 20 opening the opposite valve part t' . During the working stroke of the piston q' therefore steam may escape in the position shown in Fig. 1 through the left-hand pipe r past the left-hand valve part t' to the 25 exhaust outlet v . When again steam is admitted at the left-hand end of the cylinder, the left-hand valve part t' closes against its seat and the same process as described above takes place past the right-hand valve part 30 t' . It will be seen that this construction is exceedingly simple and in order to cut out the automatic auxiliary exhaust valve all that is necessary is for the operator to close the cocks s .
 35 It is to be noted that with the arrangement described the right-hand valve part t' will only be pressed to its seat with full pressure so long as admission continues, while the left-hand valve part will be gradually subjected to increasing pressure. When cut off is earlier and the speed of the 40

engine increased the automatic double valve will therefore gradually decrease in effective action as the speed of the engine increases so that even if by neglect the cocks s are left 45 opened the ordinary normal operation of the engine is not seriously interfered with. In order however to obtain maximum efficiency at normal running the cocks s should be closed. 50

I claim—

1. In a double acting uni-directional flow steam engine, in combination with a cylinder having inlet ports at its ends and separate exhaust ports arranged about the center of the cylinder, a piston adapted to overrun and control said exhaust ports at and near the end of its working stroke, a steam operated auxiliary exhaust valve, connections leading from about the ends of the cylinder to opposite sides of said valve, and closing members in said connections. 55

2. In a uni-directional flow steam engine, in combination with a cylinder having inlet ports at its ends and separate exhaust ports arranged about the center of the cylinder, a piston adapted to overrun and control said exhaust ports at and near the end of its working stroke, a double valve, having oppositely faced valve parts articulated together, a casing in which said valve is mounted and guided, an outlet from said casing and disposed between said valve parts, connections leading from about the ends of the cylinder to opposite sides of 60 said casing and cocks in said connections. 70

In witness whereof I have hereunto set my hand in the presence of two witnesses.

JOHANN STUMPF.
